UNITED STATES PATENT OFFICE.

WILLIAM HILLMAN, OF MOUNT VERNON, NEW YORK.

PACKING FOR PISTON-RODS.

No. 850,159.

Specification of Letters Patent.

Patented April 16, 1907.

Application filed May 10, 1906. Serial No. 316,069.

To all whom it may concern:

Be it known that I, WILLIAM HILLMAN, a citizen of the United States, residing at Mount Vernon, Westchester county, New York, have invented certain new and useful Improvements in Packing for Piston-Rods and the Like, of which the following is a full, clear, and exact description.

My invention relates to improvements in packings, particularly of advantage when used to form steam-tight joints for piston-rods and the like.

The object of the invention is to provide a simple and effective construction. The packing is flexible or elastic.

In the drawings, Figure 1 is a perspective view of the metallic element of the packing as it appears during the process of construction. Fig. 2 is a sectional view thereof as it appears when completed, taken on the line X X, Fig. 3. Fig. 3 is a view of the under side of a portion of the metallic element of the packing. Fig. 4 is a cross-section on the plane of the line Y Y, Fig. 5, showing the structural formation of the completed packing. Fig. 5 is a longitudinal sectional view of a portion of the finished article. Fig. 6 is a sectional view of a modification.

1 represents the backing or main body portion of the packing. This body portion is formed of a suitable fabric-like material in which asbestos, for example, is interwoven. This fabric is rolled up to the proper size, the several layers being, if desired, cemented together by a suitable cementing element not affected by heat. The backing when finally formed has an outline in cross-section substantially rectangular—that is, adapted to the space into which it is to be inserted when in use. Within an outer fold of the backing is inclosed or held the metallic element thereof, which may be termed a "facing." This metallic element is illustrated at 2. The construction of this element comprises a strip of suitable antifriction metal—for example, an alloy, such as Babbitt metal—and while the said strip may be formed in any desired way it is preferably formed of a tube-like member, such as is illustrated in Fig. 1, said tube being slotted or recessed through one side, as shown, to form a series of connecting or transverse bars, between which the material of the backing may find a suitable anchorage when the entire body of the packing is compressed into its final shape. This anchorage prevents the creeping of the metallic

portion of the packing relatively to the backing. It also serves to more intimately hold said elements together against stripping. These slits or recesses perform a further function—to wit, they weaken the strip to such an extent that the desired flexibility may be had, the solid portion of the strip being of course sufficiently thick to prevent breakage in ordinary use. 33 represent the slits or recesses above referred to.

4 represents a holding-flap, which may be in the form shown in Fig. 4, one edge of said flap being integral with the backing. This flap may be folded over the imperforate and unslotted surface of the metallic facing, and the extreme edge may be secured to the body of the backing, so as to hold the metallic portion in intimate contact with the main body of the backing. Here again a suitable cementing element may be employed.

The entire body portion is preferably impregnated or treated with a suitable lubricant, which serves to increase the effective life of the article.

Fig. 6 illustrates a modification in which the metallic facing-strip 2 may be covered by an envelop 5, of suitable material. In this modification the core 1^a of the body portion may be formed in any suitable way and 85 of any suitable material. It in turn may have an outer covering or envelop, (indicated at 6.) This covering 6 may inclose the bottom and sides of the core, while the upper edges may embrace partly or entirely the 90 envelop 5 of the facing-strip.

It should be understood that I have not attempted to show all of the modifications that my invention is susceptible of, but have elected to show only preferred forms thereof, 95 the fundamental or essential idea being to provide a metallic facing-strip which shall have a continuous or unbroken bearing face or surface and a slotted or recessed rear face, the advantages of said recesses or slits being 100 set forth above. By this construction the metallic portion may be uniformly and closely fitted to the piston-rod and may be held in intimate contact by the elastic and flexible backing portion. By reason of the 105 construction of the metallic portion the packing is sufficiently flexible to be applied to various sizes of piston-rods. By having the bearing-surface of the metallic portion continuous or unbroken the greatest possible 110 amount of antifriction material is provided and the durability and effectiveness of the

packing is substantially enhanced. By having the bearing-surface continuous it is likewise apparent that there will be no opportunity for particles of foreign matter to become lodged thereon, and hence the danger of scoring the rod is entirely eliminated.

These and other advantages will be apparent to the mechanic skilled in the use of such materials.

10. What I claim is—

1. A packing for piston-rods and the like comprising, a metallic strip having a continuous exposed bearing-face and a slotted or recessed rear face, and a flexible and elastic 15 backing applied to the rear face of said metallic portion.

2. A packing for piston-rods and the like comprising, a metallic strip having a continuous exposed bearing-face and a slotted or recessed 20 rear face, and a flexible elastic backing applied to the rear face of said metallic portion, said metallic portion being formed of two thicknesses of metal connected at one edge.

3. A packing for piston-rods and the like comprising, a metallic strip having a continuous 25 exposed bearing-face and a slotted or recessed rear face, and a flexible elastic backing ap-

plied to the rear face of said metallic portion, said metallic portion being formed of two thicknesses of metal connected at both 30 edges.

4. In a packing for piston-rods, an exposed facing member having an unbroken bearing-face, an elastic and flexible backing of fabric-like material built up in layers, 35 said layers being cemented together, and slits or recesses in the rear surface of the facing member, a portion of said backing projecting into said slitted or recessed portion thereof. 40

5. In a packing for piston-rods and the like, a metallic facing-strip having a continuous unbroken exposed bearing-surface, a recessed rear face, a backing portion of flexible material in engagement with said recessed 45 surface of the facing, and a retaining-flap extending from one side of said backing portion to the other side thereof and over said facing member.

WILLIAM HILLMAN.
